UNITED STATES PATENT OFFICE.

ROBERT ARCHER, SR., OF FORT WASHINGTON, PENNSYLVANIA.

COMBINED MATCH HOLDER AND ASH RECEIVER.

Application filed September 11, 1925. Serial No. 55,783.

The object of this invention is to provide improvements in combined match-holders and ash-receivers of such portable nature as are readily adapted for use as paper weights 5 as well.

Another object is to provide an ash-receiver, comprising upwardly extending walls, normally mounted upon a removable base, and a cover hingedly mounted upon one of 10 said walls and comprising a match-box holder, normally forming a closure for the space within said walls, and when released automatically swinging backward so as to expose the interior of said holder.

15 A further object is to provide such an ash-receiver with integral lugs upon one of its walls, a helical spring extending between said lugs and hingedly supporting a matchbox holder, a wire member supported by said spring and engaging the inner side of the supporting wall, and a resiliently positioned latch normally securing said box-holder in closed position, and upon being released permitting said spring through said wire member to automatically oscillate said holder and box into open position to expose the interior 25 of said walls.

Still another object is to provide in such a device a receptacle comprising side walls 30 provided with a laterally extending lug adjacent to their lowermost edge portions, and a base member normally forming a closure for the lower portion of said receptacle and having an elastic spring member extending 35 between fixed supporting means, the central portion of said spring member being adapted to be shifted laterally for the passage of said lug, after which said member returns to its normal position and operates to yieldingly 40 secure said lug, and thereby removably secure said base in operative relation with said walls.

And a still further object is to provide in 45 such a device a latch for retaining the matchbox holder in closed position, said latch comprising a pin or screw extending through a portion of one of the side walls of the receptacle and upon its protruding free end supporting one end portion of a coil spring, 50 in the other end of said spring there being mounted a pin having a head adapted to engage the match-box holder to retain the same in closed position when desired, and the end portion of said spring extending freely and 55 forming a lug for manual operation of said latch by deflecting said spring until said pin

head is removed from said box-holder, and permits the latter to rise and open.

With these and other objects in view, the present invention comprises additional novel 60 details of construction and operation herein-after fully brought out in the following description, when read in conjunction with the accompanying drawings, in which Fig. 1 is a front elevation of one embodiment of the 65 invention; Fig. 2 is a side elevation of the same, with the lid or closure in open position; Fig. 3 is a top plan view of the bottom wall or closure; Fig. 4 is a fragmentary bottom plan view of the upper portion of the 70 receptacle; Fig. 5 is a vertical longitudinal section of the device; Fig. 6 is a perspective view of the automatic wire closure-opening member; and Fig. 7 is a fragmentary sectional view of the latch mechanism. 75

Referring to the drawings, a receptacle is formed within end walls 1 and front and rear walls 2 and 3, said walls being united at their lateral edge portions and upwardly merging into a peripherally extending plane flange 80

4. The upper portion of the rear wall 3 is also provided with spaced lugs 5, carrying integral aligned ears 6, which extend into and support the opposite end portions of a helical spring member 7. 85

The respective ears of said spring member proper extend laterally beyond said lugs and are curved so as to provide inwardly opening loops 8, adapted to receive the lower portion of a frame comprising parallel walls 9, 90 connected at one side by a wall 10 and uniting to receive and support any suitable type of match-box 11. 95

Referring to Figs. 2, 5 and 6, there is illustrated a wire frame member, comprising oppositely extending end portions 12, which are normally positioned within the helix of the spring 7 as shown in Fig. 5, and from which extend laterally positioned arms 13, which, as shown in Figs. 2 and 6, are looped downwardly in parallel relation, and thence reversely at 14 and connected to form a lug extension normally engaging the inner surface of the rear wall 3 of the receptacle when the box-holder frame 9-10 is in lowered 100 position, and serving as a closure for the otherwise open upper end of the receptacle. 105

The front wall 2 is recessed at 15, said recess being limited downwardly by an inwardly extending offset portion 16, through 110 which extends upwardly a screw 17, having a threaded end portion 18, around which is

secured the lower end portion of a laterally flexible helical spring 19. This last-named spring supports in its upper free end a pin 20, having a head 21, and thence extends 5 freely to form a lug 22, which can be manually actuated so as to flex the spring and laterally shift the head 21, so as to release the adjacent edge portion of the box holding frame from the position shown in Fig. 10 1, and permit the spring 7 through the wire member 12—14 to oscillate the closure into the position shown in Fig. 2.

Either in closed position as shown in Fig. 1, or open as shown in Fig. 2, the combined 15 box-holder and receptacle closure permits matches to be readily extracted from the box in the usual manner, but only when the closure is open can matches, tobacco ashes, and the like, be dropped into the receptacle.

20 At their lower ends, two of the opposite walls of the receptacle are provided with integrally extending aligned lugs 23. Corresponding portions of the upper surface of a bottom wall are provided with spaced lugs 25, between which are secured laterally yielding, helical spring members 26, as shown in Figs. 3 and 5.

The bottom wall or closure is provided with a peripheral shoulder or flange 27, 30 which operates to fix the walls 1 and 2 of the receptacle against lateral movement with respect thereto, and to prevent their separation other than by a directly upward movement of the side and end walls with 35 respect to said bottom closure. With the lug and spring construction as described, the act of forcing the upper portion of the receptacle upon the bottom serves to deflect the springs 26 from their normal position within 40 the downward path of the lugs 23.

However, after the passage of said lugs into the position shown in Fig. 5, the springs 26 return to the normal positions and thereby yieldingly retain the inner end 45 portions of said lugs beneath them, and prevent the accidental removal or separation of the said upper and bottom portions of the receptacle, but which removal, however, may be readily accomplished by manually pulling them apart. In this case, the springs 26 are 50 again flexed inwardly at their central portions towards each other until the lugs 23 are permitted to pass by them, and the bottom closure is thereby released from the side 55 walls of the receptacle, and the burnt matches and tobacco ashes may be emptied therefrom.

Having thus described my invention, what I claim and desire to protect by Letters 60 Patent of the United States is:—

1. A receptacle, comprising side walls, a base, a pair of oppositely extending lugs carried by said walls, and a pair of laterally yielding members secured at their respec-

tive opposite ends to said base and permitting the passage of said lugs by flexing, and normally gripping said lugs to yieldingly secure said base to said walls. 65

2. A receptacle, comprising side walls provided with oppositely directed lugs, a helical spring extending between said lugs and supporting a frame adapted to support a match-box and normally forming a closure for the interior of said receptacle, and a frame member supported by said spring and engaging one of said walls, whereby said spring upon being released automatically raises said first frame to expose the interior of said receptacle. 70

3. A receptacle, comprising bottom and side walls, a pivotally mounted frame adapted to support a match-box and serve as a closure for said receptacle, and a latch comprising a coil-spring having one end secured to one of said walls and carrying a head operative to engage and yieldingly retain said frame in closed position, said spring also being extended to form a lug for manually flexing said spring and releasing said latch. 75

4. A receptacle, comprising a side wall having a lug, a separable base having a pair of lugs, and a spring extending between said base lugs and adapted to flex laterally to permit the passage of said wall lug, and thereafter operative to cooperate with said wall lug to secure said wall to said base. 80

5. A receptacle, comprising side walls, laterally extending oppositely positioned lugs carried by a plurality of said walls, a separable base having pairs of lugs, and springs extending between the lugs of the respective pairs, and the central portion of each spring being adapted to flex laterally to permit the passage of a corresponding wall lug, and said springs thereafter cooperating with said wall lugs to secure said receptacle wall to said base. 100

6. A receptacle, comprising side walls surrounding an end portion having an opening, a pair of oppositely directed lugs carried by said end portion, a helical spring extending between said lugs, a member adapted to form a pivotally mounted closure for the opening in said end portion of said receptacle and supported by the terminal portions of said spring, and a member also supported by said spring between its points of contact with said lugs and normally engaging one of the walls of the receptacle, whereby said spring, normally extending torsionally, upon being released automatically raises said closure through cooperation of said last-named member with the receptacle wall to expose the interior of said receptacle. 110

In testimony whereof I have affixed my signature.

ROBERT ARCHER, SR.
